UNITED STATES PATENT OFFICE.

GUSTAF E. TURNSJO, OF ST. PAUL, MINNESOTA, ASSIGNOR TO RAO MANUFACTURING COMPANY, OF MINNEAPOLIS, MINNESOTA.

FILM-HANGING DEVICE

1,394,697.

Specification of Letters Patent. Patented Oct. 25, 1921.

Application filed March 11, 1921. Serial No. 451,617.

To all whom it may concern:

Be it known that I, GUSTAF E. TURNSJO, a citizen of the United States, residing at St. Paul, in the county of Ramsey and State 5 of Minnesota, have invented certain new and useful Improvements in Film-Hanging Devices, of which the following is a specification.

My invention relates to film hanging devices, and an object is to provide a device in which any desired number of film hanger units may be supported in spaced relation to each other and readily increased or decreased in number. Another object is to 10 provide a film hanger unit which is so constructed that any desired number may be locked together upon a supporting member and held in place upon the supporting member by securing one of said units thereto. 15 Another object is to provide the film hangers with means for holding and protecting the orders corresponding to the particular films so that the orders for the films will not only be prevented from becoming confused but 20 will also be prevented from becoming soiled. 25

The full objects and advantages of my invention will appear in connection with the detailed description, and the novel features embodied in my inventive idea will be particularly pointed out in the claims. In the 30 accompanying drawings which illustrate the application of my invention in one form,

Figure 1 is a view in vertical section showing my invention used in connection with a 35 treating tank. Fig. 2 is a view in vertical section on the line 2-2 of Fig. 1. Fig. 3 is a view in horizontal section on the line 3-3 of Fig. 1. Fig. 4 is an elevational view 40 showing my clip detached and from the opposite side with relation to that shown in Fig. 2. Fig. 5 is a view in section on the line 5-5 of Fig. 4.

Referring to the construction shown in the drawings, the numeral 10 designates a 45 supporting bar which may be of wood or other suitable material, and is adapted to support a plurality of hangers each of which is made as a separate unit and is adapted to have a film clip attached at its lower end. 50 These hangers are stamped from sheet metal and are so constructed that when in place on the bar 10 they will be held together on account of each one engaging the next one, and these hangers are all alike with the excep-

tion that the last one is bent somewhat differently from the others so that it may be secured directly to the bar, and thus hold all of the other hangers from sliding movement thereon. Each hanger unit consists of a body portion 12 which is provided with an 60 opening 14 for receiving the bar 10, this opening being produced by cutting three sides thereof and turning the inclosed material from the uncut upper side outwardly at right angles in order to form the flange 65 16 above the opening 14. Another opening 18 is formed in similar manner but as shown in Fig. 2 this opening has its lower portion narrower than its upper portion whereby a locking member 20 is formed. At the uncut 70 bottom of this latter opening, the metal is bent away at right angles to form the flange 22 extending away from the body portion of the hanger in the opposite direction from the flange 16 and separated therefrom by the 75 uncut strip 24 which is left in the plane of the body portion. It is apparent that on account of cutting out the opening 18 in this manner, the outward portion of the flange 22 is wider than the portion adjacent the 80 body of the hanger, and as shown in Fig. 3, this wider portion of the flange is provided with a number of notches 26. The end hanger is cut out in the same manner as all 85 of the other hangers and is the same except that the flange 22 is bent downwardly to form an intermediate portion 28 and the outer end portion is then bent upwardly to provide a horizontal portion 30 which is provided with a hole to receive a screw or 90 securing device 32. Pivoted at 33 to the top of each hanger is a cap 34 which in the position shown in Fig. 1 is adapted to hold a paper 36 containing the order corresponding to a particular film and which, when 95 turned into the dotted position shown in Fig. 2, releases the paper so that it may be readily removed. The caps in this manner not only serve to prevent confusing the orders for the different films but also serve 100 to protect the paper carrying the order from becoming soiled by the chemicals or otherwise. Secured to each hanger at 38 is a resilient member 40 having a tongue 42 at its upper end for engagement with the bar 10 and having a projection 44 at its lower end adapted to fit into a hole in the lower end of the hanger. The projection 44 when 105

the device is in use extends through a hole 46 in the upper end of a film clip 48 having a pair of jaws, one of which at its lower end is provided with teeth 50 adapted to extend into holes 52 in the lower end of the other jaw for holding a film F.

The operation and advantages of my invention will be readily understood from the foregoing description. Any desired number of hanger units may be placed on the bar 10 and secured thereto in the following manner.

The first hanger is slid on the end of the bar being placed on the left hand end as viewed in Fig. 1. The flange 22 is allowed to extend out beyond the end of the bar and the second hanger is attached to the first one by sliding the locking member 20 of the second hanger up into any one of the notches 26 of the first hanger according to the particular spacing desired. The two hangers thus locked together are slid along the bar so that the flange 22 of the second hanger is left projecting beyond the end of the bar and successive hangers are attached in the same manner until the desired number are positioned along the bar. These hangers are all positively locked together and are slid along together as they are added one after the other. When the last hanger has been locked to the adjacent one and slid on to the bar the screw 32 is screwed down through the opening in the horizontal flange 30 into the material of the bar. This last hanger when thus secured serves to hold all of the hangers securely in spaced relation upon the bar and the number of hangers may be readily increased or decreased upon removal of the end hanger which serves to secure the other hangers in proper position upon the bar. The spacing between the hangers may be varied as they are being placed on the bar according to which one of the notches 26 of any particular hanger is engaged by the locking member of the succeeding hanger and the free end of the flange 22 of any particular hanger will overlap more or less the flange 22 of the succeeding hanger. The hangers when attached to the bar may be used for suspending films in different treating tanks such as the tank T shown in Fig. 1 and may be used for suspending the films in the air for drying. The clips 48 may be readily applied to and detached from the lower ends of the hangers on account of the resiliency of the member 40. The flanges 16 which rest upon the top of the bar in connection with the fingers underneath the bar keep the hangers in upright position so that the films cannot come into contact with each other even when the bar is supported in other than a horizontal position.

I claim:

1. A film-hanging device comprising a supporting member, a plurality of hanger

units adapted to be supported by said member, interengaging means on said hanger units for locking them together, and means on the last one of said units for securing it to said supporting member whereby all of said hanger units will be secured in position on said supporting member.

2. A film hanging device comprising a supporting bar, a plurality of hanger units adapted to be supported by said bar, locking members on said hanger units for engaging notches on the adjacent hanger unit, and means on the last one of said units for securing it to said bar whereby all of said hanger units will be secured in position on said bar.

3. A film hanging device comprising a supporting bar, a plurality of hanger units adapted to be supported by said bar, horizontal flanges on said hanger units each of which is provided with a number of notches, locking members on said hanger units adapted to be engaged in any one of the notches on the adjacent hanger unit, and means on the last one of said units for securing it to said bar whereby all of said hanger units will be secured in position on said bar.

4. A film hanger unit comprising a body member, a flange on said body member formed by bending out a partly cutout portion of the material, said flange having a notch and a locking member formed by one of the edges of said cutout portion, said locking member being adapted for engagement with the notch of an adjacent film hanger unit.

5. A film hanger unit comprising a sheet metal body member, a flange on said body member formed by bending out a partly cutout portion of the material, said flange being adapted to rest upon a supporting bar passed through the opening thus formed, and a tongue secured to said body member and adapted to engage the lower side of said bar.

6. A film hanger unit comprising a sheet metal body member, a flange on said body member formed by bending over a partly cutout portion of the material, said flange being adapted to rest upon a supporting bar passed through the opening thus formed, a resilient member secured to said body member, a tongue on the upper end of said resilient member adapted to engage the lower side of said bar, and means on the lower end of said resilient member for holding a film clip.

7. A film hanger unit comprising a body member, a cap on the upper end of said body member for securing and protecting a film order, and means on the lower end of said body member for holding a film in depending position.

8. A film hanger unit comprising a sheet metal body member, a cap pivoted on the upper end of said body member for securing

and protecting a film order, and means on the lower end of said body member for holding a film in depending position.

5. A film hanger comprising a sheet metal body member, a cap pivoted on the upper end of said body member for securing and protecting a film order, a resilient member

secured to said body member, and means on the lower end of said resilient member for holding a film clip. 10

In testimony whereof I hereunto affix my signature.

GUSTAF E. TURNSJO.
